BEST AVAILABLE COP
UNITED STATES PATENT OFFICE

WILLIAM W. GRISCOM, OF HAVERFORD COLLEGE, PENNSYLVANIA.

SWITCH OR CIRCUIT-CHANGER.

SPECIFICATION forming part of Letters Patent No. 393,365, dated November 27, 1888.

Application filed June 30, 1888. Serial No. 218,688. (No model.)

To all whom it may concern:

Be it known that I, WILLIAM W. GRISCOM, a citizen of the United States, and a resident of Haverford College, in the county of Montgomery and State of Pennsylvania, have invented certain new and useful Improvements in Switches or Circuit-Changers, of which the following is a specification.

My invention is an improvement in switches or circuit-closers.

The object is to provide a switch that shall make contact more certainly and avoid the introduction of additional resistance, while the construction of the switch is mechanically stronger and more durable than anything heretofore known or used.

Prior to my invention it was not possible to produce a satisfactory switch of this description for operation with currents of great intensity. Cast-brass is found to furnish the desired conductivity and to possess many other valuable qualities; but heretofore when the proper extent of surface contact was employed it was difficult or impossible to arrange two contacting surfaces which would always register with the same degree of friction and produce the same perfection of electrical contact, if, indeed, such a switch was not at times inoperative. I am by my invention enabled to utilize cast-brass for switches of almost any extent of contact-surface and thus make use of its valuable properties by constructing the contacting surfaces in two or more divisions each, thus dividing the necessary spring between several branches, all of which contribute to increase the conductivity. The definite relation existing between the cast-brass and the special form of switch devised by me enables the attainment of this very desirable result.

I provide for one contact-point a casting of metal—as brass—which is divided or bifurcated. This I arrange upon a bolt, pivot, or bearing, so that it forms a radial arm having a rotating movement. Around this central contact I arrange in a circumference having the pivot or bearing of the first-named contact as a center two or more complementary contacts, each of which consists of a casting having a bifurcated free terminal, the space between the two branches thereof being just sufficient to admit the two branches of the first-named or

rotating contact. The two branches of both contacts are thus given a spring, and both are thus caused to yield when coming into contact. It is this particular feature which renders this construction possible and which gives the beneficial results derived from the use of my switch, for I can thus make both branches of both bifurcations of greater strength and rigidity and greater conductivity than is the case with instruments of a similar nature heretofore invented, and when coming together all four contacts yield or spring sufficiently to make a complete gripping contact possible—that is to say, I divide up the necessary spring or movement among four branches, instead of confining it to one or two branches, as heretofore.

The accompanying drawings illustrate my invention.

Figure 1 is the simplest form of construction showing my improvements. Fig. 2 is a cross-section at line 2 2, Fig. 1. Fig. 3 is a modification embodying the same improvements; and Fig. 4 is a cross-section on the line 4 4, Fig. 3.

In Fig. 1, *b* is a base-board of insulating material. *A* is a casting of brass. *a* and *a'* are bifurcations thereof having considerable rigidity and but little spring. Casting *A* is mechanically connected or fixed to spindle *f* and *8c* has bearings in the base-board *b*, thus providing for a movement of rotation. Located near to the center of movement in a circumference the radius of which is about equal to the length of the bifurcated arm *A* are two brass castings, *B* *B'*. Each casting *B* *B'* has a bifurcation, *c* *c'*, Fig. 2. The space separating *c* and *c'* is about equal to the distance from the upper surface of *a* to the under surface of *a'*, so that the bifurcated contact *a* *a'* may enter between the bifurcations *c* *c'*, and the slight spring possessed by each division *a* *a'* *c* *c'* furnishes a general movement or spring sufficient to admit one pair of bifurcations between the second or complementary pair. The castings *A* and *B* are provided with cylindrical holes *s* and screws for clamping the ends of the electric circuits into position, as is well known.

In Figs. 3 and 4 the same improvements are embodied; but there is provision made for a "double-pole" circuit-changer, the castings *A* and *A'* being in two main leads, respectively,

the complementary contacts B and C being in the same leads and the contacts B' and C' being located in a second or alternative pair of leads. In this case the castings A, A' are connected by a bar of insulating material, *i.*

What I claim, and desire to secure by Letters Patent, is—

1. In a switch or circuit-changer, the combination of two bifurcated castings of metal forming the two terminals of a divided circuit, the bifurcations of one terminal entering between the bifurcations of the second, whereby extended surfaces are placed in contact under spring-pressure, substantially as described.
- 15 2. The combination, in a switch or circuit-

changer, of a bifurcated casting fixed to a rotary bearing in a base of insulating material and forming one terminal of a divided circuit, and one or more bifurcated castings fixed in position in a circumferential line of which said arm forms the radius, said castings being insulated from each other and forming complementary contacts for said arm, the bifurcations of one casting entering between the bifurcations in the other, substantially as described. 25
